STRUCTURE AND METHOD OF PREPARING
SAME FOR RAILROAD CROSSINGS

John H. Cone, Baytown, Tex., assignor, by mesne assignments, to Standard Oil Development Company, Elizabeth, N. J., a corporation of Delaware

Application November 18, 1948, Serial No. 60,737

2 Claims. (Cl. 238—8)

1

The present invention is directed to an improved structure and method for preparing same which is useful in roadways. More particularly, the invention is directed to a reinforced asphaltic cement which is capable of standing severe shock.

It has been known for a considerable number of years that asphalts either natural or those produced from oil and coal tar may be used in preparing roadways. In fact, since the time of macadam, asphalt has become increasingly useful as a road construction material.

It has also been known to mix the several kinds of asphalt including those derived from oil, coal tar, and natural sources with aggregate, sand, and mineral fillers to impart to the asphalt mechanical strength which it has lacked to some degree. Thus, properly designed mixes of aggregate, sand, mineral filler and asphaltic cement have been mixed and applied hot for use in road construction for the past several decades. Roads constructed in this manner have performed very satisfactorily provided proper foundations were laid and provided they were not subjected to localized shock. It has been observed that one weakness of this type of construction is its inability to withstand sudden severe shocks under heavy traffic such as has been observed at railroad crossings and at street bus stops. Under these particular conditions, localized areas are exposed to shocks by heavy, fast moving traffic quickly losing momentum by sudden application of the vehicle's brakes. Thus, tremendous forces are exerted against the asphaltic concrete surface. Rapid loading and unloading of the asphaltic surface in this manner usually produces, after repeated application of the forces, heaving of the surface and internal surface breaks.

A similar condition prevails at railroad crossings where the asphaltic mat extends over the crossing. In primary highways this condition may be corrected by placing steel or concrete mats adjacent to the rails. In secondary and feeder roads the mats are usually applied over the total track crossing. Under these conditions after short periods of exposure to the heavy traffic the asphalt may heave and become displaced within a comparatively short period of time.

In concrete roadways it has also been the practice to stop the concrete short of the actual railroad crossing and to employ asphaltic fillers of the type mentioned to make available a continuous roadway. It has been observed that under these latter conditions the asphalt becomes cracked and squeezed from areas adjacent the

rails and fails after a short exposure time requiring its replacement.

It is, therefore, an object of the present invention to provide an improved method for preparing an asphaltic mat which is capable of withstanding heavy and repeated severe shock.

Another object of the present invention is to provide an improved structure comprising a reinforced asphaltic concrete.

10 The objects of the present invention may be achieved by providing an improved asphalt structure in roadways and in areas receiving heavy loading and unloading which includes a binder course and a surface course intermediate of which and embedded therein are placed criss-crossed reinforcing steel rods.

The invention may be briefly described as involving the laying of a binder course on the area to be protected in accordance with the present invention following which a layer of criss-crossed reinforcing steel rods or other metallic rods having sufficient mechanical strength are superimposed thereon. The steel reinforcing rods may be embedded at points in the binder course. 25 Above the layer of the reinforcing rods is laid the surface course which is then compacted and finished to make the finished roadway.

The binder course employed in the present invention will usually have a composition approximating that given in the following table:

TABLE I

Stone Gradation:	Percent:
Passing 1 1/4" screen	100
Passing 1" screen	97-100
Passing 1" screen, retained on 1/2" screen	0-65
Passing 1/2" screen, retained on 1/4" screen	10-50
Passing 1/4" screen, retained on 10 mesh	10-25
Passing 10 mesh screen	20-35
Asphalt, weight %	2.5-5.5

Thus, it will be seen that the binder course will include stones of various gradations and asphalt.

The surface course which is laid above the reinforcing rods may have a composition as shown in Table II.

TABLE II

Percent:
Aggregate passing 1/2" screen
Aggregate passing 3/4" screen
Aggregate passing 3/8" screen, retained on 10 mesh
60-75

Aggregate passing 10 mesh, retained on	
40 mesh	3-10
Aggregate passing 40 mesh, retained on	
80 mesh	6-12
Aggregate passing 80 mesh, retained on	
200 mesh	4-10
Aggregate passing 200 mesh	4-8
Asphalt, wt. %	4-6

It will be seen that similar to the binding course the surface course also contains aggregate of different gradations.

The stones and aggregate employed in the practice of my invention may include gravel, crushed rock such as crushed limestone, pea gravel, oyster shell, and many other minerals which have characteristics which will impart mechanical strength to roadways. Low grade iron ore has been used in building roadways including asphalt may also be used in my invention. It will be understood, of course, that the stones, ore, aggregate, and the like must be properly sized before using.

The amount of asphalt employed in my invention will vary widely over a range from about 2% by weight to about 15% by weight of the roadway. Usually an amount in the range between 2% and 10% by weight will give satisfactory results.

The asphalt employed in both the binder and surface courses may be either an oil, coal tar, or a natural asphalt. Oil asphalts may be obtained by light hydrocarbon precipitation such as propane precipitation of heavy crude petroleum fractions or by distillation of crude petroleum to the heavy residual fractions. The coal tar asphalts are usually the heavy fractions remaining after the destructive distillation of coal tar. The natural asphalts may be obtained from the natural sources such as from the Island of Trinidad and many other natural sources which are known throughout the world.

The penetration of the asphalt employed in usual road building will vary depending on the type of roadway, but usually will include a penetration for the binder course of an average of about 55 penetration to about 135 penetration while the surface course will usually include an asphalt penetration of about 55 to about 90.

The steel rods employed in the method of the present invention and in producing the improved structure is a lattice work of steel rods. A convenient size of the steel rods may be about $\frac{1}{4}$ inch in diameter. Although rods of this size are preferred, larger rods up to about $\frac{3}{4}$ inch in diameter may be used. These steel rods may be crisscrossed and welded to form a lattice or mesh whose openings are either rectangular or diamond shaped.

The invention will now be further illustrated by reference to the drawing in which Fig. 1 is a view looking downward on an asphaltic concrete roadway which is crossed by a railroad, and

Fig. 2 is a detail showing one method of anchoring the steel mesh or mat to the individual rails of the railroad of Fig. 1.

Referring now to the drawing, numeral 11 designates a roadway including an asphaltic concrete surface which crosses a railroad 12 consisting of parallel rails 13 and 14. In the improved method of preparing the structure, a base course such as a binder course of the type illustrated in Table I is laid adjacent the parallel rails 13 and 14 and in between the parallel rails. Over this base course in the area between the two parallel rails 13 and 14 and for a distance of about three feet extending on each side of the rails is laid a specially constructed lattice work 15. This

lattice work is constructed of steel rods having diameters of about $\frac{1}{4}$ inch and which are crisscrossed and welded to form a coarse mesh as indicated in the drawing. The end of each particular rod of the mesh is positioned perpendicular to the rails and may be bent downwardly at an angle of 90° to form footings 16. These footings 16 are turned down from the horizontal about 3 inches and are driven into the binder course as an anchor for the lattice work. The other end of the lattice work is also turned under at an angle of 90° to form second footings 17 to allow the lattice work to be anchored to the rails 13 and 14. These footings 17 turn from the horizontal about 1 inch and are designed to engage rings 18 and to anchor the steel lattice work or mat to the rails. After the lattice work has been properly constructed and anchored both to the rails and to the binder course, a surface course is then applied over the entire road area including the lattice work and the area extending past the lattice work. The roadway is then compacted and thus the lattice work of steel mesh is firmly anchored and embedded in the roadway on which the shock occurs.

By attaching the steel lattice work to the rails by rings, slots, hooks, shoulders, and other engaging means, vertical movement of the rails will be permitted as a train passes over the crossing. While not shown in the drawing, it will be understood that it is the usual practice for rails 13 and 14 to be supported by wooden cross ties. With the arrangement of the present invention, the rails and supporting wooden cross ties may move downwardly under the load as the train passes over the rails while the structure consisting of lattice work 15 and the binder and surface courses need not move downwardly but instead may remain supported by the earth between said cross ties and by the earth beyond the ends of the cross ties. It will be understood that as the train passes over the rails the cross ties, not shown in the drawing, may not be subjected to a single downward movement followed by a single upward movement but in addition the ends may vibrate in a vertical plane and if in such vibration the motion in the upward direction carries said cross ties above their normal unloaded position an upward thrust will be transmitted to the structure consisting of the binder course, lattice work 15 and surface course. However, the major force transmitted by the movement of the train over the rails is in the downward direction. It will be understood that as the train passes over the steel rails there is no automotive traffic on the crossing so that the steel rails move up and down under the effect of the train wheels, while the structure consisting of lattice work 15 and the binder and surface courses are substantially free from stresses. Then after the train has passed and automotive traffic uses the crossing, the lattice work 15 with binder course and surface course is supported both by the earth between the cross ties and by the earth beyond the ends of the cross ties so that this structure is adequately supported for automotive traffic.

It will be understood, of course, that I do not intend to limit myself to steel lattice work since other metals having sufficient mechanical strength may be substituted therefor. For example, alloys of nickel, chromium, steel, and some of the non-ferrous metals and alloys thereof may be substituted for the steel, although the latter is preferred. As examples of the non-ferrous metals may be mentioned magnesium and alumi-

num and the like. Alloys of zinc, copper, tin, beryllium, iron, chromium, nickel, and the like, may also be used in my invention.

Figure 2 shows a detail of a means of attaching steel mat 15 to one of the steel rails 13 and also illustrates a method of attachment of the steel mat 15 and the footings 16 and 17. It will be seen by reference to Fig. 2 that the footings 17 engage with rings 18 while the footings 16 engage with the binder course.

The nature and objects of the present invention having been fully described and illustrated, what I wish to claim as new and useful and to secure by Letters Patent is:

1. A method for preparing an improved railroad crossing wherein first and second parallel steel rails cross a roadway, including the steps of attaching spaced rings on each side of said first and second rails, forming a mixture consisting of asphalt and stone passing a $1\frac{1}{4}$ inch screen in an amount between 85% and 93% by weight, forming a binder course of said mixture on the road foundation between said parallel rails, forming a binder course of said mixture on the roadway adjacent each of said rails for a distance greater than 3 feet from each of said rails, forming a first steel lattice including a web of $\frac{1}{4}$ inch diameter steel rods having a width equal to the width between said rails with ends of the rods bent downwardly at an angle of 90°, placing said first web on the binder course between said parallel rails with the bent ends of the rods slidably engaging rings attached to said first and second rails, forming second and third steel lattices each including a web of $\frac{1}{4}$ inch diameter steel rods with the width of approximately 3 feet with ends of the rod bent downwardly at an angle of 90°, placing the second web on the binder course at the side of the first rail, slidably engaging ends of one side with rings attached to the side of the first rail and driving the ends of the other side into the binder course, placing the third web on the binder course at the side of the second rail, slidably engaging ends of one side with rings attached to the side of said second rail, and drawing the ends of the other side into the binding course, forming a second mixture consisting of asphalt and aggregate passing a $\frac{1}{2}$ inch screen in an amount between 85 and 98% by weight, covering said binder course and said first, second and third webs with the second mixture to form a surface layer and compacting said layer with said binder course.

2. An improved railroad crossing having first and second parallel rails crossing a roadway, rings attached to each side of each of said rails, a binder course of stone passing a $1\frac{1}{4}$ inch screen and asphalt on the roadway between said rails and on the roadway for a distance greater than 3 feet on each side of each of said rails, a first steel lattice including a web of $\frac{1}{4}$ inch diameter steel rods arranged between said parallel steel rails on said binder course with ends of the rods on parallel sides of the web bent downwardly at an angle of 90° and fitting slidably in rings attached to the sides of the first and second rails, a second lattice including a web of $\frac{1}{4}$ inch diameter steel rods and extending a distance of at least 3 feet arranged adjacent the side of the first rail with ends of the rods at one side of the web bent downwardly at an angle of 90° and slidably engaging rings attached to the side of the first rail and ends of the rod at the other side of the lattice work bent at an angle of 90° and driven into the binder course to serve as an anchor, a third steel lattice work including a web of $\frac{1}{4}$ inch steel rods and extending at least 3 feet arranged adjacent the second rail with ends of the rods at one side of the lattice bent at an angle of 90° and slidably engaging with rings attached to the side of the second rail and the ends of the rod at the other side of the lattice work bent downwardly at an angle of 90° and driven into the binder course as an anchor, and a surface course super-imposed on said first, second and third lattices and compacted with said binder course, said surface course including an aggregate passing a $\frac{1}{2}$ inch screen and asphalt.
